Primary Examiner — Lauren D McVey

CLAIM

The ornamental design for computer LCD monitor stand, as shown and described.

DESCRIPTION

FIG. 1 is a left side view of the computer LCD monitor stand showing my new design;

FIG. 2 is a right side view thereof;

FIG. 3 is a back view thereof;

FIG. 4 is a front view thereof;

FIG. 5 is a top view thereof;

FIG. 6 is a bottom view thereof;

FIG. 7 is a perspective view thereof; and,

FIG. 8 is a perspective view thereof in an alternate position in an environment.

The broken lines depict portions of the computer LCD monitor stand that form no part of the claimed design.

1 Claim, 8 Drawing Sheets
